CREEPER DEVICE FOR SHOES

Filed Jan. 11, 1927

INVENTOR
William Potter
BY
Howard C. Thompson
ATTORNEY

UNITED STATES PATENT OFFICE.

WILLIAM POTTER, OF NEW YORK, N. Y.

CREEPER DEVICE FOR SHOES.

Application filed January 11, 1927. Serial No. 160,367.

This invention relates to what is known as creeper devices for use in connection with shoes, and particularly the heel structure of a shoe to prevent slipping or sliding of the feet on slippery or icy pavements, roadways and the like; and the object of the invention is to provide a device of the class specified provided with one or more resiliently supported prongs adapted to be projected beyond the lower face of the heel of a shoe to engage a slippery or icy surface to prevent the slipping of the feet, said prongs having sufficient resiliency to provide for comfortable walking, and yet engage the slippery surface sufficiently to prevent slipping; a further object being to provide means for moving the prong or prongs into operative and inoperative position and for retaining the same in inoperative position, said means comprising, in one method of carrying my invention into effect, a bail-like member adapted to be placed within the instep portion of the shoe when the device is in inoperative position and to encircle the heel of the shoe when the device is in operative position; a further object being to provide means for supporting the device in connection with the heel of a shoe; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of a part of a shoe showing one of my improved devices mounted in connection therewith and in inoperative position.

Fig. 2 is a view similar to Fig. 1 but showing the device in operative position.

Fig. 3 is a partial section on the line 3—3 of Fig. 2.

Fig. 4 is a view similar to Fig. 2 but showing a slight modification.

Fig. 5 is a bottom plan and sectional view of the structure as seen in Fig. 4.

Fig. 6 is a bottom plan and sectional view

of the heel portion of a shoe and showing a modified form of attachment; and,

Fig. 7 is a section on the line 7—7 of Fig. 6.

In the construction shown in Figs. 1 to 3 inclusive, I have shown a keeper device comprising a bail-like member 10 fashioned from a heavy wire or rod into yoke formation, preferably of such dimensions as to encircle the rear portion of the heel 11 of a shoe. The ends of the wire from which the member 10 is formed are curled about screws 12 to form springs 13, and the ends of said wire are extended from the springs 13 to form prongs 14 which are arranged adjacent the side edges of the heel 11 of the shoe as clearly seen in Fig. 3 of the drawing, and which, when in operative position as seen in Figs. 2 and 3, project below the lower face of the heel 10 or the rubber heel facing 11^a constituting part of the heel structure. It is also to be noted that the prongs 14 are arranged rearwardly of the screws 12 so that in the process of walking when the device is in use, the prongs may spring backwardly as indicated in Fig. 2 of the drawing, as the heel of the shoe comes in contact with the surface over which the shoe passes. This result is accomplished by the spring 13 employed, and it will be apparent that the prongs 14 will be forced into the ice or other slippery surface sufficiently to definitely fix the shoe and prevent sliding or slipping. The prongs 14 function as spikes as will be apparent.

It will be understood that the device may be attached to a shoe heel of any kind or class and by any suitable devices. When used in connection with a rubber heeled shoe, I prefer to employ a tube 15 which is seated within the recesses formed on the adjacent faces of the heel 11 proper and the rubber heel facing 11^a, the tube 15 having a reinforcement of canvas or other material 15^a. In practice, the screws will pass between the adjacent faces of the flattened tube 15 and the threads thereof engage the canvas 15^a to securely retain the screws against displacement. It will be understood that the heel facing 11^a will be secured to the heel proper in the usual or any desired manner.

I also preferably mount a pin or screw

16 on one side of the heel 11 in such position as to engage one of the prongs 14 when the bail member 10 is swung into the position shown in Fig. 1 of the drawing or beneath the instep of the shoe in order to retain the creeper attachment against accidental displacement when in inoperative position. The device will be supported in operative position by the tensional engagement 10 with the member 10 with the heel of the shoe.

In Fig. 4 of the drawing, I have shown a slight modification wherein the spring 13 of the device is curled upon pins or studs 18, riveted to attaching plates 18, the plates 18 being of substantially L-formation and provided at their respective ends with prongs 19 and 19' adapted to be driven into the shoe heel in securing the plates thereto. Said 18 plates are provided with outwardly extending bodies 20 to take the place of the pin or screw 16 in connection with which the prongs 14 will operate to support the device in inoperative position, as will be apparent. The device may be employed in connection with a solid or all leather heel 11^b or a combination leather and rubber heel similar to that. At this time, I also call attention to the fact that my invention 30 is not limited to use in connection with heels of any particular form and construction, it being understood that the attachment will be constructed or designed to suit the particular type of heel in connection with which 38 the same is employed.

In Figs. 6 and 7 of the drawing, I have shown another modification wherein a single prong or spike 21 is mounted upon a shaft or rod 22 by curling the wire from 40 which the prong 21 is formed in the manner of a spring 23 on said rod. In this form of construction, the rod 22 is mounted between the heel 24 proper and the facing member 24^a thereof, which may be composed of rubber, and the rod is keyed in place and against displacement by an enlarged collar 25, the rod and collar seating in recesses on the adjacent faces of the parts 24 and 24^a, and said rod extending through 50 one side of the heel structure and provided with an annular stock 26 by means of which the same may be rotated by the use of a key or other device. The prong 21 operates in a recess 27 opening through the lower 55 face of the heel or the part 24^a thereof so that the prong 21 may be moved into a position to project below the lower face of the heel or be moved into an inoperative position as indicated in dotted lines in Fig. 60. Sufficient friction will be provided between the rod 22 and its support to retain the same in its different positions. Aside from the specific structure employed, the prong 21 will function in the same manner 65 as the prongs 14 and will prevent the slip-

ping or sliding of a shoe over a slippery surface.

As above stated, one of the distinctive features of my invention is to provide a creeper attachment, the projecting prong or spike of which is resiliently supported, in order to provide comfortable walking, and yet presenting the required gripping means for preventing the slipping of the shoes when traversing an icy or slippery pavement. It will be understood that my improved attachment may be mounted in connection with footwear of any kind or class, and regardless of the material employed in the construction thereof. 75

While I have shown certain details of construction for carrying my invention into effect, it will be understood that I am not necessarily limited to these details, and various changes therein and modifications 80 thereof may be made within the scope of the appended claims, without departing from the spirit of my invention or sacrificing its advantages.

Having fully described my invention, what 90 I claim as new and desire to secure by Letters Patent, is:—

1. A creeper device of the class described fashioned from a wire strand coiled to form a spring, one end of which extends to form 95 a spike or prong, a pin-like member on which said spring is mounted, and means whereby when the prong is extended for use, the same may yield under the weight of the wearer.

2. A creeper device comprising a yoke-shaped body adapted to encircle the rear portion of the heel of a shoe when the device is in use, the ends of said body being curled into spring members, said spring members being mounted on pin-like bodies 100 and the ends of said spring members extending to form prongs which project beyond the lower face of the heel of the shoe when the device is in operative position. 105

3. A creeper device comprising a yoke-shaped body adapted to encircle the rear portion of the heel of a shoe when the device is in use, the ends of said body being curled into spring members, said spring members being mounted on pin-like bodies 110 and the ends of said spring members extending to form prongs which project beyond the lower face of the heel of the shoe when the device is in operative position, and means involving said pin-like bodies for coupling the 115 device to the heel of a shoe.

4. A creeper device comprising a yoke-shaped body adapted to encircle the rear portion of the heel of a shoe when the device is in use, the ends of said body being curled 125 into spring members, said spring members being mounted on pin-like bodies and the ends of said spring members extending to form prongs which project beyond the lower face of the heel of the shoe when the device 130

is in operative position, means involving said pin-like bodies for coupling the device to the heel of a shoe, and said device being movable into inoperative position and means for retaining the same in such position.

5. In a device of the class described, a yoke-shaped body fashioned from a strand of metal, the end portions of which are coiled to form spring members, and the ends of said body extending from said spring members to form prongs.

10 6. In a device of the class described, a yoke-shaped body fashioned from a strand of metal, the end portions of which are coiled to form spring members, the ends of said body extending from said spring members to form prongs, said prongs being arranged angularly with reference to the plane of said yoke-shaped body and being movable relatively thereto through said spring members.

15 7. In a device of the class described, a yoke-shaped body fashioned from a strand of metal, the end portions of which are coiled to form spring members, the ends of said body extending from said spring members to form prongs, said prongs being arranged angularly with reference to the plane of said yoke-shaped body and being movable relatively thereto through said spring members, and attaching devices passed through the 20 spring members of said device for mounting the same in connection with a shoe.

25 8. In a device of the class described, a yoke-shaped body adapted when in use to

encircle the rear portion of the heel of a 35 shoe, the ends of said body having prong members adapted to extend beyond the lower tread face of the heel when the device is in use, and the ends of said yoke-shaped body being pivotally supported in connection with 40 the shoe.

9. In a device of the class described, a yoke-shaped body adapted when in use to encircle the rear portion of the heel of a 45 shoe, the ends of said body having prong members adapted to extend beyond the lower tread face of the heel when the device is in use, said body having spring properties, and said body being pivoted to a shoe structure 50 and being adapted to be swung forwardly beneath the arch of the shoe when in inoperative position.

10. In a device of the class described, a 55 yoke-shaped body adapted when in use to encircle the rear portion of the heel of a shoe, the ends of said body having prong members adapted to extend beyond the lower tread face of the heel when the device is in use, said body having spring properties, and said body being pivoted to a shoe structure 60 and being adapted to be swung forwardly beneath the arch of the shoe when in inoperative position, and means for retaining said body in inoperative position.

In testimony that I claim the foregoing as 65 my invention I have signed my name this 8th day of January 1927.

WILLIAM POTTER.
